COMBINED TRACTOR CAB AND HOOD

Joseph A. Rinaldi, Oradell, N.J., and James F. Fulton, Mamaroneck, N.Y., assignors to Allis-Chalmers Corporation, Milwaukee, Wis.

Continuation-in-part of design application Ser. No. 371,290, June 18, 1973, and abandoned application Ser. No. 371,291, June 18, 1973. This application Sept. 20, 1974, Ser. No. 507,939

Term of patent 14 years

Int. Cl. D12—09

U.S. Cl. D40—5

Fig.2

Fig.3

Fig. 4

Fig. 5

FIG. 1 is a right front perspective view of a combined tractor cab and hood embodying our new design, it being understood that the broken lines are for illustrative purposes only;

FIG. 2 is a left side perspective view thereof;

FIG. 3 is a left front perspective view thereof;

FIG. 4 is a front perspective view thereof; and

FIG. 5 is a rear perspective view thereof, it being understood that the hood has been omitted for clarity of illustration.

The undisclosed top is flat and unornamented.

This is a continuation-in-part of design application Ser. No. 371,290 filed June 18, 1973, and design application Ser. No. 371,291, filed June 18, 1973 and now abandoned.

We claim:

The ornamental design of a combined tractor cab and hood, as shown and described.
